United States Patent Office

Des. 194,548
Patented Feb. 12, 1963

194,548

TABLE LAMP OR SIMILAR ARTICLE

Leo R. Slaton, Chicago, Ill., assignor to Swiss Harmony, Inc., Chicago, Ill., a corporation of Illinois

Filed Dec. 4, 1961, Ser. No. 67,804

Term of patent 3½ years

(Cl. D48—20)

The FIGURE is a perspective view of a table lamp or similar article embodying my new design.

The side of the lamp not shown is substantially the same in appearance as the side shown.

I claim:

The ornamental design for a table lamp or similar article, as shown and described.
